UNITED STATES PATENT OFFICE.

ALEXANDER McDONALD, OF CHICAGO, ILLINOIS.

GRAIN-SHOCKING MACHINE.

1,344,348.

Specification of Letters Patent. Patented June 22, 1920.

Application filed October 20, 1919. Serial No. 331,866.

To all whom it may concern:

Be it known that I, ALEXANDER McDONALD, a subject of the King of Great Britain, and a resident of Chicago, county of Cook, and State of Illinois, have invented certain new and useful Improvements in Grain-Shocking Machines, of which the following is a specification.

This invention relates to shocking attachments adapted for use on grain-binding harvesters, whereby the bundles or sheaves may be collected automatically in parallel relation in groups and deposited uprightly on the ground in the form of shocks. This application is in part a continuation of my pending application Serial No. 262,599, filed November 14, 1918.

Although various attempts have been made by others to perfect a device of this general character, I am not aware that any such attachment has ever proven sufficiently dependable or efficient to meet the general need or to go into any extensive use.

The main objects of this invention are to provide a shocker of improved form and operation, better adapted for simple construction and dependable control; to provide a sheaf collector or cradle of improved construction having a concentric-motion side door and automatic means for opening and closing said door; to provide positive operating means respectively for tilting the cradle and for sliding and opening same, adapted for automatic actuation and manual control; to provide transfer means for turning the sheaves horizontally and discharging same into the shocker cradle; and to provide such a device of inexpensive design and in a form adapted for ready attachment to binders such as are already in use.

An illustrative embodiment of this invention is shown in the accompanying drawings, in which—

Figure 1 is a perspective front view of the attachment in its normal position with the cradle set ready to collect a load of sheaves.

Fig. 2 is a rear view of the device as it appears when tilted to its discharge position with the sliding door retracted to its open position.

Fig. 3 is a longitudinal section, somewhat

enlarged, through the support side of the cradle and across its supporting shaft.

55

Fig. 4 is a side elevation and shows how the shocker is mounted on a binder.

Fig. 5 is a section at 5—5 on Fig. 4.

Fig. 6 is a plan with certain parts broken away.

60

Fig. 7 is a conventional diagram of connections for the shocker.

Fig. 8 shows a combined automatic release and manual closing gear connection for the shocker.

65

In the embodiment shown in the drawings the sheaf-collecting holder or cradle comprises an end wall or head 1, a fixed wall plate 2, and a movable wall or door plate 3. Said cradle is secured firmly to a tiltably mounted support 4 of oblong rectangular shape disposed lengthwise under the lower edge of wall 2. Said support 4 includes a block 4^a and has a joint device 5 to which is connected a crank rod 5^a for reciprocating the cradle, as will be further explained. Said support 4 is secured rigidly to a short cross bar or sleeve in the form of a tube 6 which in turn is mounted slidably upon and is concentric with a horizontally positioned rod or pipe 6^a which extends a considerable distance from said support on each side.

70

The movable plate or door 3 is operatively connected to a pair of tension members or cables 7 and 7^a, the adjacent ends of which are crossed over the outside of and are fastened to the side edges of the door, as at 7^b and 7^c respectively, whereby a pull or preponderance of stress on cable 7 operates to open the door and in like manner cable 7^a serves to close it.

80

The cradle or shocker as a whole 1—2—3, it will be seen, comprises substantially a hollow frusto-conoidal body having a closure 1 at the smaller end, and including a pair of relatively movable side walls 2 and 3 to one of which said closure is fixed, and the top side being permanently open. When the movable side 3 slides downward or back past the other side 2 the top side opening virtually enlarges on the trailing side of the cradle relative to the bodily movement of the machine.

90

The construction whereby the door 3 is held in place for sliding back over the ex-

105

terior face of wall 2 includes a pair of guide flanges 1^a and 2^a secured to the closed and open ends of the cradle respectively. Said flanges are formed with free edges projecting toward each other over the exterior face of wall 2, and the corresponding edges of door 3 fit slidably between said wall face and said free edges respectively, as shown in Fig. 3.

10 Said door has a bearing strip 3^b secured to its outer face a short distance up from its lower edge as viewed in Fig. 2, which strip slides on the upper edge of said flange 2^a. A similar strip 3^a is secured in like manner 15 near the upper edge of the door and bears upon the inwardly turned lip 1^b on the lower edge of flange 1^a, so that the door 3 is supported and guided at both ends.

In use the shocker attachment operates as 20 follows: The cradle, resting normally as in Fig. 1 or with the closed end tilted downward somewhat, becomes filled with sheaves arranged with their heads toward the closed end. At the will of the operator, by means 25 of suitable control means hereinafter described, the cradle is tilted (right to left in Fig. 1) so as to dump the sheaves, butts down, in shock formation and at the same time the cradle stands still or substantially 30 so for a moment while the door 3 is opening. Next, the cradle, with its door open, is drawn forward, leaving the shock standing on the ground. Then simultaneously the door is restored and the cradle tilted back 35 ready to receive another load of sheaves. Referring to Fig. 1, this movement of the cradle on shaft 6^a is first to the left and then to the right, but as viewed in Fig. 2, the movement is first to the right and then to 40 the left.

This action is effected by the means next to be described. The pivotal rod 6^a is journaled at 8 and 9 at or adjacent to its ends for oscillation on the frame part 10 to tilt 45 the cradle. In order that the latter may be positively coturnable with said rod, the tubular shoe 6 to which the cradle is fixed is keyed slidably thereto, as by means of the spline 11 and feather 12. The frame part 50 10 is secured rigidly to the vehicle frame proper or may be formed as a part thereof. Journal bearings 13 and 14 are provided for said rod 6^a. Fixed to said rod is a crank arm 15 operatively connected for oscillatory 55 actuation automatically subject to the will of the operator, as will be understood. See Figs. 7 and 8.

In order to effect automatic reciprocation of the pitman rod 5^a, subject to the will of 60 the operator, for positive sliding of the cradle backward and forward, the front end of said rod is journaled somewhat loosely at 16 to a crank arm 17, the latter being journaled at 18 to frame 10 and being operatively connected to cooperate with the tilt-

ing means and being controlled preferably by the same manual clutch or equivalent means for power actuation as will be understood. See Figs. 7 and 8. In order to accommodate both swinging and relative 70 twisting motion at 5, the joint is adapted for universal movement and may well be in the form of a ball and socket joint, the plate 19 being provided with a socket at 19'.

The front end of cable 7 is fastened to the 75 frame at 20 and the rearward end of cable 7^a is fastened to the frame at 21, so that as the cradle moves back and forward the door plate 3 is correspondingly moved to open and restore respectively.

80 In order to transfer the sheaves from the tying and discharge end of the binder mechanism to the upper side of the cradle, an inclined belt 22 is mounted on rolls or pulleys 23 and 24, the lower one being appropriately 85 geared to the driving mechanism to effect elevating movement, as will be understood. Guide means 25 having a 90° right-hand twist project downward from the binding mechanism for depositing the sheaves, butts 90 outward, on the belt 22. From said belt the sheaves fall into the cradle.

Means 26 actuatable by the same manual device as controls the tilt and slide of the cradle, are pivoted to the frame at 27 near 95 the upper end of belt 22, to hold back the sheaves on said belt when the cradle is being operated for discharge. For this purpose the link 26' connects means 26 to the hand lever shown in Figs. 7 and 8. Said belt is 100 provided with yielding arms 22' adapted to normally engage the sheaves sufficiently to carry them upward, but the belt slides yielding under the sheaves when they are held back by the stop 26.

105 Referring further to Figs. 7 and 8, showing the shocker controlling means somewhat diagrammatically, power is transmitted from the tread wheel 28 through shaft 29 to the reducing gears 30 and 31 and thence by 110 shaft 32 to the control clutch. Said clutch includes a pair of relatively movable plates 33 and 34 connected to the ends of shafts 32 and 35 for positive coturning therewith respectively, said plates being adapted to engage each other and coact for positive mutual coturning when the clutch is set. One of said plates 34 is provided with a hub projection 36 and is slidable on said shaft 35, being splined thereto.

115 Said plate 34 is controlled by a toggle device including toggle bars 37 and 38 pivoted at 39 to each other and to a link 40. The opposite ends of said bars are connected pivotally to sleeve 41 and stationary bearing 42 respectively. Said sleeve fits in a groove in the hub 36, so that operation of the toggle slides said plate 34 into and out of engagement with plate 33. The opposite end of link 40 is pivoted to the short arm of a 120

manual control lever 43 the long arm of which has a handle 44. Said lever is fulcrumed at 45 on said bearing 42.

A spring 46 on a fixed arm 47 urges said lever toward its clutch opening position, so that when the toggle is swung past the critical point in opening the clutch it snaps over to its release position and holds the plate 34 set tightly against the stationary brake post 49, which is rigid with or a part of bearing 42 and frame 10. When the handle 44 is swung to the left the toggle is set past its neutral point and holds the clutch closed until the lever is swung back sufficiently to reverse the toggle.

Normally the lever is free to be swung manually, but automatic restoring means are provided in the form of wheel 50 keyed to shaft 35. Said wheel has a short cam flange 51 so disposed as to wedgingly bear against and swing the lever 43 to its clutch releasing position as said wheel moves through a certain angle of its rotation.

Said shaft 35 has keyed thereto a bevel gear 52 for tilting the shocker cradle, and a crank wheel 53 for sliding said cradle. Said gear 52 coacts with a bevel gear 54 which is keyed to shaft 55 on which is keyed a crank wheel 56 having a crank arm 57. Said arm 58 coacts with a link 58 the opposite end of which is pivoted to the arm 15 which tilts the cradle shaft 6^a. The arm 15 is much longer than arm 57, so that arm 57 in turning 360° causes arm 15 to turn or oscillate only about 90°, as will be understood.

The crank wheel 53, or its equivalent arm 17 of Fig. 4, supports the crank pin 16 to which the cradle slide-rod 5^a is connected.

The operation is substantially as follows: The harvester as a whole moves forward uniformly and continuously by the pull either of draft animals or a traction engine, the various parts of the harvester mechanism being arranged or geared so as to receive their power from the tractive source, for instance the tread wheel. By means of manual control means such as are well understood in the art, the attendant or driver regulates the operation of the harvester parts and especially the operation of the shocker, as shown in Figs. 7 and 8. To this end the operator observes visually when the cradle 1 is full, and then grasps the handle 44 of lever 43 and swings it to close the clutch 33—34, being to the left in Figs. 7 and 8, past the retreating edge of cam flange 51 of wheel 50.

This causes rotation of shaft 35 which in turn tilts the cradle and slides it rearward and back. Just as the rotation of shaft 35 is nearly completed, the cam 51 restores lever 43 and opens the clutch, setting the plate 34 rigidly against stop 49. The cam 51 passes the lever 43 just before the toggle 37—38 snaps over, so that the device is ready

for manual resetting at will. It will be noted that in throwing the dump mechanism into gear, the hand lever and link 26' serve to set the shock holder 26 in its effective position.

As will be apparent, the cradle virtually stands still for a moment at its rearmost upright position in dumping, and then rushes forward to its normal position as it swings back to horizontal position. As the cradle slides back, the rear wall or door 3 slides past wall 2 and permits the cradle to advance, leaving the sheaves standing on the ground.

Although but one specific embodiment of this invention has been herein shown and illustrated, it will be understood that numerous details of the construction shown may be altered or omitted without departing from the spirit of this invention as defined by the following claims.

I claim:

1. A shocker, comprising a side-opening cradle of substantially round cross-section, closed at one end and open at the other and having a side door mounted and adapted for peripheral movement to vary the degree of closure of the side opening, in combination with means adapted and arranged to tilt the cradle from a normal prostrate position to an upright open-end-down position, and means to simultaneously open said door.

2. A shocker, comprising a side-opening cradle of substantially round cross-section, closed at one end and open at the other and having a side door mounted and adapted for peripheral movement to vary the degree of closure of the side opening, in combination with means adapted and arranged to tilt the cradle endwise for dumping and restoring, and co-operative means to open and restore said door.

3. A shocker, comprising a side-opening cradle of substantially round cross-section, closed at one end and open at the other and having a side door mounted and adapted for peripheral movement to vary the degree of closure of the side opening, in combination with a shaft whereon said cradle is tiltably mounted in crosswise position and lengthwise of which it is bodily slidable.

4. A shocker, comprising a side-opening cradle of substantially round cross-section, closed at one end and open at the other and having a side door mounted and adapted for peripheral movement to vary the degree of closure of the side opening, in combination with a shaft whereon said cradle is tiltably mounted in crosswise position and lengthwise of which it is bodily slidable, said shaft being disposed horizontally in the direction of travel of the shocker as a whole, movement of said cradle along said shaft in the dumping operation being such as to about neutralize the translatory movement of the

shocker, and the side opening and door being disposed on the rearward side of the cradle, whereby the sheaves may be deposited in shock formation.

5. A shocker, comprising a side-opening cradle of substantially round cross-section, closed at one end and open at the other and having a side door mounted and adapted for peripheral movement to vary the degree of

10 closure of the side opening, in combination with door-controlling means in the form of a pair of flexible tension members attached to the longitudinal edges respectively of the door and disposed across its outer face,

15 whereby a pull on the one may serve to open the door and a pull on the other may serve to close it.

6. A shocking device, comprising a supporting rod extending in the direction of general

20 movement of the device, a cradle mounted transversely thereon in both tilting and sliding relation for normally horizontal position, said cradle being open on its upper

side to receive sheaves and also at its downwardly tilting end to drop the sheaves upon 25 the ground, and the rearward wall of said cradle being slideable downward and forward over the forward wall to clear the shock as the cradle moves forward.

7. A shocker, comprising a side-opening 30 cradle of substantially circular cross-section, closed at one end and open at the other and having a side door mounted and adapted for peripheral movement to vary the degree of closure of the side opening, in combination 35 with a shaft whereon said cradle is tiltably mounted in crosswise position and lengthwise of which it is bodily slideable, and a rod connected to said cradle for reciprocating same on said shaft, the connection for 40 said rod being adapted to permit universal movement.

Signed at Chicago this 8th day of October, 1919.

ALEXANDER ^{his} X McDONALD.
